ZERBE C. BRADFORD, OF DAYTON, OHIO, ASSIGNOR TO DELCO PRODUCTS CORPORATION,
OF DAYTON, OHIO, A CORPORATION OF DELAWARE

CENTRIFUGAL SWITCH

Application filed January 18, 1932. Serial No. 587,197.

This invention relates to centrifugal switches and especially to commutator short circuiting devices for alternating current motors particularly motors of the repulsion-induction type. One kind of commutator short circuiting device heretofore devised consists of an annulus of coil spring wire surrounding the armature shaft and enclosing a plurality of weights which move outwardly from the shaft as its speed increases and cause the convolutions of the spring to engage edges of the commutator segments in order to short circuit the commutator to cause the motor to operate as an induction motor. After a substantial number of starting operations of the motor have been performed the convolutions of the spring band become pitted due to sparking. Hence the cross sectional area of the wire of the spring band has been reduced so that it no longer acts the same way to resist movement of the weights as it did when first installed. Hence the commutator segments will be short circuited sooner than desired. It is an object of the present invention to overcome the difficulty with respect to spring band commutator short circuiting devices and this object is accomplished by a construction wherein the resilient spring band is not permitted to contact directly with the commutator segment but is enclosed within another helical coil annular band of wire of good conducting material. By means of this construction the inner band enclosing the weights and providing the mechanical resistance to outward movement of the weights is not permitted to carry any current and hence is not subjected to deterioration due to sparking. This inner band expands with increase of speed of the motor shaft to cause the convolutions of the outer band to move into engagement with the commutator bars. Although the convolutions of the outer band may become pitted due to many starting and stopping operations of the motor the short circuiting device remains operable to short circuit the commutator bars at the intended speed. Further objects and advantages of the present invention will be apparent from the

following description, reference being had to the accompanying drawing wherein a preferred embodiment of one form of the present invention is clearly shown.

In the drawing:

Fig. 1 is a fragmentary longitudinal view of an electric motor embodying the present invention.

Figs. 2 and 3 are sectional views taken on the line 2-2 of Fig. 1 showing respectively the short circuiting band in inner and outer positions.

Fig. 4 is a sectional view of line 4-4 of Fig. 5.

Fig. 5 is a sectional view of line 5-5 of Fig. 3.

Referring to the drawing 20 designates the armature shaft carrying an armature 21 revolving within a field 22 and having its windings connected with the various segments 23 of a commutator. It will be noted that the segments 23 have overhanging portions 24 projecting beyond the non-conducting hub 25 of molded material in which the tangs 26 of the commutator segments are embedded. The hub 25 is molded also to a metal sleeve 27 which is press fitted over the armature shaft 20.

The shaft 20 is provided with a groove 30 which receives a wire split ring 31 which retains a sleeve 32 which is so shaped and is so related to the hub of the commutator as to provide an annular pocket 33 for receiving the commutator short circuiting device which comprises an outer helical coil band 34 of wire of good conducting material surrounding an inner helical coil band 35 of spring wire of resilient material such as steel spring wire. Before the ends of the wire band 35 are joined together by a threaded connector 36, a number of threaded weights 37 are arranged within the coil of wire 35 before being bent into annular form.

The ends of the band 34 need not be joined together hence the band 34 does not operate to resist outward movement of the weights 37. The ends of the band 35 are joined together by the connector 36 in such a manner that the band 35 will cause the band 34 to rest against the flange 37 of the spring 32.

when the motor is at rest. The coils of the bands 34 and 35 are wound in opposite ways so that the turns of the wire will appear to cross each other as shown in Fig. 4. In this way the turns of the band 35 when contacting against the inner side of the turns of the band 34, will not be crowded down into the space between the turns of the band 34 and cause them to be wedged therein in such a manner so as to interfere with the operation of the device. By crossing the turns it is apparent that the turns of the wire 35 cannot wedge into the space between the turns of the wire bands 34. Preferably the band 35 of spring metal wire is wound left hand, and the band 34 of bare soft copper wire is wound right hand.

As the speed of the motor increases the weights 37 move outwardly against the resistance afforded by the band 35 which in turn presses the band 34 into engagement with the overhanging portion 34 of the segments of the commutator 23. Then when the speed of the motor decreases the band 35 causes the weights to move inwardly to withdraw the band 34 from contact with the commutator segments. If sparking occurs, only the band 34 will be pitted but this will not interfere with the operation of the short circuiting device since the cross sectional dimensions of the wire 35 remain unchanged throughout the life of the device.

While the form of embodiment of the present invention as herein disclosed, constitutes a preferred form, it is to be understood that other forms might be adopted, all coming within the scope of the claims which follow.

What is claimed is as follows:

40 1. A circuit controlling device comprising, in combination a shaft, an annular row of contacts carried thereby, an expansible annular band of coiled wire of good conducting material coaxial with the shaft and engageable with the contacts, an expansible annular band of coiled spring wire within the first band, and weight members cooperating with the second band.

50 2. A circuit controlling device comprising, in combination, a shaft, an annular row of contacts carried thereby, an expansible annular band of coiled wire of good conducting material coaxial with the shaft and engageable with the contacts, an expansible annular band of coiled spring wire within the first band, and weight members within the second band.

60 3. A commutator short circuiting device comprising, in combination, a shaft, a commutator carried thereby, a retainer on the shaft and cooperating with the commutator to provide an annular pocket, an expansible annular band of coiled wire of good conducting material located in said pocket and engageable with the commutator, an ex-

pansible annular band of coiled spring wire within the first band, and weights within the second band.

4. A device according to claim 3 in which one coiled wire band is wound right hand, 70 and the other band is wound left hand.

In testimony whereof I hereto affix my signature.

ZERBE C. BRADFORD.
